UNITED STATES PATENT OFFICE.

BRIDGMAN RUSSELL AND BENJAMIN RUSSELL, OF LONDON, ENGLAND.

TURBINE.

SPECIFICATION forming part of Letters Patent No. 628,635, dated July 11, 1899.

Application filed November 18, 1897. Serial No. 659,056. (No model.)

To all whom it may concern:

Be it known that we, BRIDGMAN RUSSELL and BENJAMIN RUSSELL, subjects of the Queen of Great Britain, residing at London, in the county of Middlesex, England, have invented certain new and useful Improvements in Turbines, of which the following is a full and complete specification, such as will enable those skilled in the art to which it appertains to make and use the same.

This invention relates to hydraulic-power apparatus and particularly to turbine wheels; and the object thereof is to provide a variable wheel of this class in which the flow of water through or from the wheel or through or from the buckets with which the wheel is provided may be regulated, a further object being to provide a turbine wheel which is provided with buckets of novel form and construction, whereby great power is obtained with a minimum head or supply of water.

The invention is the same as that for which Letters Patent were granted in Great Britain, No. 19,398, dated September 9, 1896, and is fully disclosed in the following specification, of which the accompanying drawings form a part, in which—

Figure 1 is a transverse section of our improved wheel and the principal parts of the mechanism connected therewith; Fig. 2, a plan view of three of the buckets which we employ, one of said buckets being shown in longitudinal section; and Fig. 3, an outside view of said buckets.

In the drawings forming part of this specification the separate parts of our improvement are designated by the same numerals of reference in each of the views; and in said drawings, reference being made to Fig. 1, we have shown at P an annular plate which supports the water-supply R, which consists of a metal ring provided at the upper side with an outwardly-directed rim R², which rests on the plate P, and at the lower side thereof with an outwardly-directed annular lip R³, and we have also shown at S the main shaft on which the turbine wheel W is mounted, and said shaft is provided at its lower end with an extension S², which in practice is mounted in a suitable support. (Not shown.)

Above the wheel W is a vertically-movable circular disk or plate A, provided with a hub

a, through which the shaft S passes, and said hub is provided at its lower end with a collar C, through which the shaft S also passes, and at its upper end with a hydraulic washer or gland L, which is designed to stop leakage through the hub a of the disk or plate A, and said disk or plate A is provided at its perimeter with vertical rods a², which pass upwardly through bearings a³, formed in the ring R, and said rods a² may be provided with any suitable means for raising and lowering the disk or plate A, and by means of this construction the space between the perimeter of the disk or plate A and the lip R³ of the water-supply R may be adjusted as desired, and the amount of water passing through said space may thus be regulated.

The wheel W is provided at its perimeter with a plurality of buckets B, which are arranged in the form of a circle thereon and which may be connected therewith in any desired manner, preferably by being riveted or screwed thereto, as hereinafter described, and said buckets are of the form shown in Figs. 2 and 3, the outer surface thereof being convex longitudinally and the inner surface being correspondingly outwardly curved, said buckets being also substantially wedge-shaped in form when viewed from above and being so shaped or curved as to give the greatest possible speed and a power in proportion to the amount of water passing therethrough or the "head" thereof.

The sides of the back portion of the buckets B are inclined toward the rear end, as shown at b in Fig. 3, and the interior of said buckets is also wedge-shaped in form, as shown in Fig. 2, and the back wall thereof is curved or concave, as shown at b², and the rear or discharge end of said buckets is open, as shown at b⁴, and much wider than the central portion or front end thereof, thus offering the least resistance to the tail-water and providing for a more ready discharge thereof after its effective work has been done.

The sides of each of the buckets B, at the wider or discharge end thereof, are also preferably provided at their inner edges with triangular projections b⁵ and at the narrower or forward end with similar short triangular projections b⁶, and at one side of said buckets the projections b⁵ and b⁶ are countersunk, forming

spaces b^7 , in which are placed tie-plates b^8 for securing the buckets together.

In connecting the buckets and in connecting the same with the wheel W, as described, 5 the projections b^5 overlap the projections b^6 and serve to brace and retain in position the ends of the buckets.

The projections b^5 and b^6 and the tie-plates b^8 are not absolutely essential, however, as 10 said buckets may be held in place by being bolted to the wheel W, as shown at G.

In Fig. 3 we have shown the outer side of 15 a portion of the water-wheel consisting of three of the buckets B, and this view also shows the inclined sides b at the rear or discharge end of said buckets, hereinbefore referred to, said buckets being thus made substantially V-shaped in cross-section at their discharge end, as shown at b^4 , and by reason 20 of this construction the pressure of the water as it is discharged from the bucket acts on the curved back wall throughout its entire length, and in case of a thin stream or partial head of water a proportionate effect is 25 obtained, and the action on each of the buckets is the same throughout the entire perimeter of the wheel.

By means of the vertically-adjustable disk or plate A the amount of water entering the 30 buckets may be regulated, and by raising said disk or plate until it touches the annular lip R^3 on the under side of the water-supply ring R the supply of water to the buckets may be entirely cut off and the wheel stopped, as will 35 be readily understood.

Having fully described our invention, we 40 claim as new and desire to secure by Letters Patent—

1. A water-wheel, comprising a central circular portion provided with buckets secured 45 to the perimeter thereof, said buckets being curved and wedge-shaped in form, the inner sides thereof being open, and the discharge end thereof being also open and V-shaped in cross-section, said buckets being also provided at each end with side projections, and

said projections on one side of said buckets being countersunk, and tie-plates secured in said countersunk portions for connecting said buckets, substantially as shown and described. 50

2. A water-power apparatus constructed as herein described, and comprising a suitably-supported circular water-supply, the bottom of which is provided with an annular outwardly-directed flange or rim, a vertical shaft passing centrally through said water-supply, a wheel mounted on the lower end thereof, the perimeter of which is provided with a plurality of detachable buckets, and a vertically-movable disk or plate mounted on said shaft within said buckets, and provided with rods which pass upwardly through bearings connected with said water-supply, said disk or plate being adapted to operate in connection with said annular flange or rim for regulating the supply of water to said buckets, substantially as shown and described. 55

3. In a water-power apparatus, the combination with a circular water-supply ring, provided with an outwardly-directed annular flange or rim, of a shaft passing centrally therethrough, and a wheel on the lower end of said shaft provided at its perimeter with a plurality of detachable buckets arranged in 60 a circle thereon, and inclosing said annular flange or rim, and a disk or plate mounted on said shaft and provided with rods which pass upwardly through bearings connected with said water-supply ring, said disk or plate being vertically movable, the perimeter of said disk or plate being projected below said flange or rim, substantially as shown and described. 65

In testimony that we claim the foregoing as 70 our invention we have signed our names, in presence of the subscribing witnesses, this 2d day of November, 1897.

BRIDGMAN RUSSELL.
BENJAMIN RUSSELL.
